SAFETY POINT BAR FOR FLAT KNITTING MACHINES

Francis Tait, Jr., Philadelphia, Pa., assignor to
 Howard Hosiery Company, Sinking Spring, Pa.,
 a corporation of Pennsylvania

Application January 22, 1936, Serial No. 60,199

3 Claims. (Cl. 66—96)

My invention relates to a new and useful safety point bar for flat knitting machines, whereby all damage to the stocking, in the process of manufacture, is substantially entirely eliminated.

5 My invention relates to the device described, which is easily and inexpensively produced and which can be used in conventional flat knitting machines without any interference with, or alteration to, any of its parts.

10 Point bars heretofore used on flat knitting machines, whether the same be "welter" point bars, which are used in knitting the leg, whether they be "transfer" point bars, which are used for transferring the leg of the stocking from the 15 legger to the topper, or whether they be "topper" point bars, which are used in knitting the foot of the stocking, have heretofore been made of substantially, elongated bars between which the "welter" or "topper" points (or needles) are held, 20 said bars being secured together by means of a plurality of screws which are substantially flush with the surfaces of the bars. Such conventional bars are satisfactory when new, but as soon as one or more points break so that it becomes necessary to unscrew the parts for the 25 purpose of replacing the points, and in view of the necessity of firmly clamping the parts together, the screw heads become mutilated by the screwdriver thus developing burrs, which catch 30 the stockings being knitted, thus damaging the stockings and causing great loss.

Prior to the present invention the cause of excessive numbers of damaged stockings has been more or less a mystery in the various manufacturing plants, as witnessed by the fact that the operators of the knitting machines have been ordered to remove their rings, if any, during the knitting of the stockings, on the theory that the jewelry referred to was the cause of the excessive 40 numbers of pulled threads from the torn and otherwise damaged stockings.

As a result of this first hand experience in the plant with which I have been connected for many 45 years I discovered that the cause of the damaged stockings rested almost exclusively in the mutilated screw-heads of the point bars, and I have accordingly devised a novel construction of a point bar which completely and effectively cures this defect.

The construction and advantage of my novel safety point bar will be more fully explained in the annexed specification and the accompanying drawings, in which,

55 Fig. 1 represents a plan view of a point bar

embodiment my invention, certain parts being broken away to show the internal construction.

Fig. 2 represents a side elevation of Fig. 1, certain parts being shown in section.

Figs. 3 and 4 represent sections on lines 3 and 4, respectively, of Fig. 1.

Fig. 5 represents a view similar to Fig. 1 showing a slightly modified construction.

Fig. 6 represents a view similar to Fig. 1 showing further modification of my invention.

Fig. 7 represents a side view of Fig. 6, certain parts being shown in section.

Fig. 8 represents a section on line 8—8 of Fig. 7.

Figs. 9 and 10 represent sectional views similar to Fig. 8 showing further modification of the invention.

Referring to the drawings in which like reference characters designate like parts, my novel point bar consists of the bottom or base bar 1 to which is clamped a top bar 2 by means of 20 the screws 3, the points 4 being clamped between the bars 1 and 2, with or without the interposing of the felt or strip washer 5, the points 4 being deflected at their inner ends, as at 6, to engage holes or seats 7 in the base bar 1. In a conventional construction the heads of the screws 3 would be flush with the surface 8 of the top bar 2, and, when the heads of the screws 3 are mutilated by a screwdriver, a catch on the stocking would be made, causing threads to pull and otherwise damage the stocking. In order to overcome this difficulty I have formed a recess in the upper surface of the top bar 2 in which recess I positioned the cover plate 10 which completely covers the heads of the screws 3, which 35 secure the bars 1 and 2 and the points 4 together. The cover plate, or bar 10, is secured to the top bar 2 by means of the screws 12, which being offset with relation to the bottom surface 13 of the base bar 1, and being positioned at either 40 end of the point bar, are not in a position to cause any damage, the ends of the shanks of the screws 12 being polished flush with the upper surface 8 of the top bar 2, as at 14. The cover plate 10 is further secured to the upper bar 2 by 45 means of the screw 15 which is counter-sunk, as at 16, and the end of the shank of which is also smoothly polished to be flush with the upper surface 8 of the bar 2, as at 17. The ends of the shanks of the screws 3 are also polished smooth 50 with the under surface 18 of the base bar 1, as at 19. In this construction, when it is necessary to replace any of the points 4, the screws 12 and 15 are removed, which permits the removal of the cover plate 10 to render the screws 3 accessi-

ble. This permits manipulation of the screws 3 for the purpose of replacement of the parts of the points and, when the device has been re-assembled with the heads of the screws 3 prob- 5 ably damaged or roughened, the cover plate 10 is replaced and the point bar again presents a smooth surface which does not in any way damage the stockings.

In the construction shown, in Fig. 1 the cover plate 10 is shown as having a dove-tail connection with the upper bar 2, as at 20, this dove-tail connection being at right angles with respect to the longitudinal axis of the bar. In Fig. 5 I have shown the identical construction except that the 15 dove-tail connection between the cover plate 10 and the upper bar 2 forms an acute angle, as at 21, so that the upper plate 10 to be positioned in place must be inserted from the rear edge of the upper bar 2 in a direction facing, or towards, 20 the points 4. In Figs. 6, 7 and 8 I have shown a modified form of construction in which the cover plate 10 is adapted to slide over the upper bar or plate 2 from either end thereof, the upper plate 2 being provided with a longitudinally beveled re- 25 cess while the cover plate 10 is provided with longitudinally beveled edges to produce a dove-tail connection along the entire length of the bar, as best seen at 22.

In Fig. 9 I have shown a modified form of construction in which, in lieu of a longitudinal, dove-tail connection, I utilize the longitudinally rab- 30 beted connection best shown at 23.

In Fig. 10 I have shown a further modified construction in which, like Figs. 8 and 9, the cover 35 plates 10 slides longitudinally over either end of the bar 2, but in which the upper plate 10 is provided with the inwardly deflected flanges 25 which engage oppositely beveled, longitudinal edges or recesses 24 of the upper bar 2.

40 In the construction shown in Figs. 6 to 10 in- clusive, due to the fact that the cover plate 10 firmly engages the upper bar 2 along its entire length, it becomes unnecessary to utilize a plu- 45 rality of screws for holding the cover plate 10 to the assembly, as shown in Figs. 1 to 5, and a single screw 26 at either end of the bar will be sufficient to hold the cover plate 10 in position.

It will thus be seen that by my novel construc- 50 tion I have produced a point bar which can be utilized wherever needed in flat knitting machines to eliminate the necessity of changing the screws

3 every time that they are removed for the purpose of replacement or repair of the points 4, and that my novel construction presents a smoother outer surface than is presented even by a new conventional point bar, thereby eliminating the 5 heretofore costly excessive damage attending the knitting of the stocking.

It will also be seen that the covering of the screws 3 by the addition of the cover plate 10, 10 in any of the manners set forth, does not inter- 15 fere with, or in any way alter, the ultimate, fin- ished appearance or dimensions of the conven- tional point bar so as in any way to detract from its efficiency or capacity to be used with existing knitting machines. 15

Having thus described my invention what I claim as new and desire to secure by Letters Patent is;

1. A safety point bar for flat knitting machines comprising two longitudinal elements adapted to 20 clamp the points there-between, fastening de- vices passing through said elements and having their heads embedded in one of said elements and a cover plate seated in a cut-out formed in said last mentioned element to cover the heads of said 25 fastening devices, said cover plate being secured to said two longitudinal elements by means of counter-sunk fastening devices completely in- accessible to the stocking fabric on said bar. 30

2. The combination with a point bar for flat 35 knitting machines comprising two longitudinal elements adapted to clamp the points there-be- 40 tween and screws passing through and fastening said longitudinal elements together, of a cover plate presenting an externally smooth surface and seated in a cut-out formed in the one of the 45 two elements in which the heads of said screws are embedded to prevent the stocking fabric on said bar from catching on the heads of said screws. 50

3. A safety point bar for flat knitting machines comprising two longitudinal elements adapted to clamp the points there-between, fastening de- 45 vices passing through said elements and having their heads embedded in one of said elements, and a cover plate seated in a cut-out formed in said last mentioned element to cover the heads of said 50 fastening devices, there being a tongue and groove engagement between said cover plate and said cut-out.

FRANCIS TAIT, JR.
